G. R. TUCKER,
COTTON SCRAPER ATTACHMENT,
APPLICATION FILED DEC. 15, 1920.

1,411,818.

Patented Apr. 4, 1922.

UNITED STATES PATENT OFFICE.

GUY R. TUCKER, OF CITRA, OKLAHOMA.

COTTON-SCRAPER ATTACHMENT.

1,411,818.

Specification of Letters Patent.

Patented Apr. 4, 1922.

Application filed December 15, 1920. Serial No. 430,912.

To all whom it may concern:

Be it known that I, GUY R. TUCKER, a citizen of the United States, residing at Citra, in the county of Hughes and State 5 of Oklahoma, have invented certain new and useful Improvements in Cotton-Scraper Attachments, of which the following is a specification.

This invention relates to scraper blades 10 and more particularly to a scraper blade attachment whereby the earth working element may be adjustably mounted in different angular positions to meet the necessities of the desired cultivation.

One of the objects of the invention is 15 directed to a scraper blade attachment capable of universal use in connection with various types of cultivator blades, said device being constructed and arranged for attachment and detachment to a support or foot piece of the modern cultivating machine.

A still further object of the invention resides in the provision of a scraper blade 25 attachment having a novel form of clamping means for positively locking and retaining the blade in various predetermined angular positions without effecting the efficiency and operation of the machine.

Another and important object of the invention will be found in the simplicity of 30 construction, reliability of its several parts, which may be easily assembled by the unskilled mechanic, capable of being manufactured at a comparatively low cost, and 35 the universal use of which the same is applicable.

With these objects in view and others 40 which will be manifest and suggested as the nature and purpose of my invention are 45 revealed in the following specification and drawing wherein I have shown a practical, yet preferred embodiment thereof.

Figure 1 is a rear view partly broken 45 away showing the attachment when assembled.

Fig. 2 is a view taken on the line 2—2 of Fig. 1.

Fig. 3 is a view taken on the line 3—3 50 of Fig. 1.

Fig. 4 is a similar view taken on the line 4—4 of Fig. 1.

Referring now in particular to the illustration wherein I have shown my novel and 55 improved scraper blade attachment mounted on the foot piece or standard 1 of a modern

cultivator, it being understood that the right and left scraper blades are adapted to be used in the cultivation of rows or hills. It will be noted that the rear face 2 of the 60 scraper blade 3 is adjustably attached to a curved cuff designated by the numeral 4, which cuff is provided with a reduced upper extension 5 having an elongated, elliptical slot 6. A threaded bolt 7 having a locking 65 nut and washer 6 thereon passes through an aperture 10 usually provided in the scraper blade, said bolt passing also through the elongated slot 6 permitting the ready adjustment of the blade subsequently to be referred to.

The cuff as shown is provided with another aperture 11 extending therethrough near its lower portion and receives a rivet 12 passing through an aperture 13 in the 75 scraper blade retaining the said bolt and cuff in locked position, the head 14 of said bolt being counter-sunk in the recess 15 as clearly shown in Fig. 2. The cuff is also provided with an enlarged intermediate 80 elongated curved recess 16 which receives the transverse bolt 17 passing through an aperture in the curved clamping member 18 and the foot piece 1 where the said bolt is secured by a nut and washer 19, 20, also 85 shown in Fig. 3 of the drawing. The curved face of the cuff member is preferably corrugated as at 21 for locking engagement with the serrations 22 of the curved clamping member.

In accordance with the above structural arrangement, it will be readily apparent that by loosening the bolt and nut 17, 19 and of course, the bolt and nut passing through the elongated slot 6, the scraper blade may 95 be raised or lowered to the desired angle with respect to the ground to effect the necessary scraping action of the blade. Furthermore, the serrated locking clamp also permits the blade to be turned on its vertical 100 axis with respect to the foot piece or support in the manner shown by dotted lines in Fig. 3.

In the accompanying drawing, I have illustrated my invention embodied in one 105 form by way of example, and which in practice has been found to be highly satisfactory in obtaining the desired results. It will be obvious however that other embodiments may be adopted, and that various changes 110 in the details of construction may be resorted to by those skilled in the art without

departing from the spirit and scope of the invention. It is furthermore understood that the invention is not necessarily limited or restricted to the precise elements shown except in so far as such limitations are specified in the subject matter being claimed.

I have shown the curved cuff and clamping member used in connection with a scraper blade but it is to be understood however, that the invention is not necessarily limited to the particular type of blade employed since it is capable of use in connection with various types of cultivating tools, as will be readily apparent to those skilled in the art.

What I claim is:
A cultivator blade attachment in combina-

tion with a support comprising a curved cuff member, having an offset reduced upper extension provided with an elliptical slot therein, fastening elements passing through apertures in the blade and slot for vertically adjusting said blade, said cuff member being also provided with an elongated, intermediate recess and corrugations on its inner face, a curved clamping member having cooperating serrations seated entirely within the inner face of the cuff, and a central pivot bolt extending through the cuff, clamps and supports whereby the clamping member and the blade may be circumferentially adjusted.

In testimony whereof, I affix my signature hereto.

GUY R. TUCKER.
